NONREFILLABLE ATTACHMENT

Carlos F. Hernandez, Mexico City, D. F. Mexico

Application May 21, 1936, Serial No. 81,109

5 Claims. (Cl. 215—30)

This invention relates to a non-refillable attachment for bottles, jugs and containers, and is designed primarily for use in connection with bottles containing high grade liquors and wines, but it is to be understood that the attachment in accordance with this invention may be employed in any connection for which it is found applicable.

The object of the invention is to provide, in a manner as hereinafter set forth, an attachment 10 of the class referred to, which, when in anchored position with respect to the neck of the bottle, jug or container, will prevent the surreptitious refilling of the bottle, jug or container after the original contents of the latter have been discharged.

A further object of the invention is to provide, in a manner as hereinafter set forth, an attachment for the purpose referred to which will permit of a steady discharge, with no surging action, of the contents of the bottle, jug or container when the latter is tilted from the vertical to beyond the horizontal.

Further objects of the invention are to provide, in a manner as hereinafter set forth, a non-refillable attachment for bottles, jugs and containers which is simple in its construction and arrangement, readily installed with respect to the neck of a bottle, jug or container, strong, durable, compact, thoroughly efficient in the use intended thereby and comparatively inexpensive to manufacture.

With the foregoing and other objects which may hereinafter appear, the invention consists of the novel construction, combination and arrangement of parts as will be more specifically referred to and are as illustrated in the accompanying drawing wherein is shown an embodiment of the invention, but it is to be understood that changes, variations and modifications may be resorted to which fall within the scope of the invention as claimed.

In the drawing:

Figure 1 is a perspective view.

Figure 2 is a vertical sectional view illustrating the attachment anchored to a bottle neck.

Figure 3 is a view similar to Figure 2 with the structure inverted.

Figure 4 is a top plan of the valve seating forming element.

Figure 5 is a section on line 5—5, Figure 4, and Figure 6 is a top plan view of the stop element.

The attachment includes a hollow cap or housing element 1 of substantially semi-elliptical contour, a stop element 2, a weighting element 3, a valve element 4, a combined outlet and valve seat forming element 5 and a sealing element 6.

The element 1 is constructed from any suitable material and formed at its outer end with a discharge opening 7 and on its inner face with spaced conducting-off channels 8 extending

lengthwise thereof communicating at their outer ends with the opening 7. The element 1 between its transverse median and its inner end has its outer face formed with an annular shoulder 9.

The element 2 is formed of any suitable material and is positioned within the element 1. The element consists of an inverted cup-shaped circular body 10 of arcuate cross section formed with a series of openings 11. The element 2 is arranged within element 1 intermediate the ends 10 of the latter. The diameter of element 2 is such with respect to the inner diameter of element 1 to permit the shifting of element 2 within element 1 for a portion of the length of the latter. The element 2 constitutes a stop for the weighting element 3 which will now be referred to.

The weighting element 3 is formed of any suitable material and is positioned within the element 1 rearwardly with respect to element 2. The weighting element 3 consists of a solid body 20 formed of an outer rounded portion 12, a circular intermediate portion 13 and an inverted frustoconoidal rear portion 14 formed with a flat rear end 15.

The valve element 4 is formed of any suitable material and consists of a disc-like body 16 provided on its rear face and axially of such face with a rearwardly directed stem 17 which is flared at its point of joinder with the body 16, as indicated at 18.

The combined outlet and valve seat forming element 5 is formed of any suitable material and consists of a disc-like body 19 cut out to form a pair of oppositely disposed segmental-shaped spaced beveled edges 20, a rectangular opening 21, a pair of oppositely disposed dished out portions 22 leading to the walls of the opening 21 and a pair of oppositely disposed, outwardly inclined opposed wall forming portions 23 which lead from said beveled edges to the side walls of the opening 21. The valve element 4 seats upon the element 5 and the stem of the latter is arranged between the wall forming portions 23. The flared upper part of the stem 17 normally seats on the beveled edges 20. The wall forming portions 23 are inclined outwardly with respect to the beveled edges 20. The dished out portions 22 facilitate the passage of the fluid through the element 5. The body 19 of the element 5 is suitably secured to the inner face of the element 1 at the inner end thereof.

The element 6 is in the form of a resilient gasket 24 which is arranged against the rear edge of the element 1 and positioned upon the edge of the bottle neck 25.

Any suitable means may be employed for anchoring the element 1 to the bottle neck 25 in a manner whereby the element 6 will be compressed to provide a seal between the element 1 and bottle neck 25. By way of example, a means 60

for such purpose is indicated at 26 and bears against the shoulder 9 of element 1 and also against the peripheral shoulder 27 of the bottle neck 25.

5 The part of largest diameter of the element 5 is of less diameter than the inner diameter of the element 1. The diameter of the element 4 is less than the diameter of the element 5.

When the bottle is in an upright position, the 10 element 3 which is arranged in the element 1 will be positioned in the manner as shown in Figure 2, and will hold down valve element 4 whereby the valve element 4 will act as a closure to prevent the passage of liquid through element 15 5. The element 3 functions to maintain the element 4 in the position shown in Figure 1 as the element 3 has its flat inner end 15 seated on the outer face of the valve element 4. When the bottle is shifted to below the horizontal the 20 weighting element 3 moves off of the valve element 4 permitting the latter to be shifted off of the element 5 and allowing the contents of the bottle to pass through element 5, around element 4 and 3 through channels 8, through discharge opening 7 and also through the openings 11 in element 2. When the bottle is moved to below horizontal and the element 3 shifts towards the discharge opening 7, the element 2 will be carried therewith until it wedges against 25 the inner face of the element 1 thereby providing a stop to arrest the outward shift of element 3. When element 2 wedges against the inner face of element 1, the conducting-off channels 8 are not closed whereby the discharge of the 30 contents of the bottle will not be arrested. When the bottle is in upright position, the valve element 4 constitutes a closure for the bottle.

What I claim is:

1. A non-refillable attachment for the purpose set forth comprising a hollow cap element 40 adapted to be anchored upon the neck of a container, said element being open at its outer and inner ends, the open outer end of said element constituting a discharge outlet, said element being formed lengthwise of its inner face with spaced 45 conducting-off channels communicating with said outlet, a stationary valve seat forming element arranged within said cap element at the inner end of the latter and formed with means 50 for the discharge of the contents of the container

into said cap element, a shiftable valve element for seating on said valve seat forming element arranged within the cap element for closing and including a part extending into said means, a shiftable weighting element normally seating on 5 said valve element for maintaining the latter in closing position relative to said means, and a perforated stop element positioned within said cap element between the discharge outlet of the latter and the weighting element. 10

2. The invention as set forth in claim 1 with the cap element being of semi-elliptical contour, and the stop element being of a diameter to shift for a portion of the length of and to wedge against the inner face of the cap element to arrest the shifting of the weighting element. 15

3. A non-refillable attachment for the purpose set forth including a hollow cap element of semi-elliptical contour adapted to have the edge of its inner end clamped with the edge of the neck of 20 a container and provided at its outer end with a discharge outlet, said element being formed on its inner face with spaced conducting-off channels communicating with said outlet, a valve seat forming element secured within the inner 25 end of said cap element and formed with means for the discharge of the contents of the container into said cap element, a shiftable valve element mounted on the valve seat forming element for normally closing said means and being formed with a stem arranged in said means, a shiftable weighting element for normally maintaining the valve element in closing relation with respect to said means, and a shiftable perforated stop element for said weighting element having 30 its movement in one direction limited by the coaction of a part of the inner face of the cap element with the edge thereof. 35

4. The invention as set forth in claim 3 having said stop element of inverted cup shape and 40 of segmental contour in cross section, said weighting element having an outer end of rounded contour to abut the stop element and a flat inner end for seating on the valve element.

5. The invention as set forth in claim 3 having 45 combined therewith a compressible sealing means between the inner end edge of the cap element and the edge of the neck of the container.

CARLOS F. HERNANDEZ.
